[57] CLAIM

The ornamental design for a tumbler or similar article, as shown and described.

DESCRIPTION

FIG. 1 is a side elevational view of a tumbler or similar article showing my new design; the sides not shown are similar to the side shown;

FIG. 2 is a top plan view thereof;

FIG. 3 is a sectional view thereof taken along line 3—3 of FIG. 2; and

FIG. 4 is a bottom plan view thereof.

FIG. 1.

FIG. 3.

FIG. 2.

FIG. 4.
